MAURICE AUGUSTE EUGÈNE LEBLANC, OF SURESNES, FRANCE, ASSIGNOR, BY MESNE ASSIGNMENTS, TO GENERAL ELECTRIC VAPOR LAMP COMPANY, OF HOBOKEN, NEW JERSEY, A CORPORATION OF NEW JERSEY

MEANS FOR OPERATING MERCURY SWITCHES

Application filed June 13, 1927, Serial No. 198,612, and in France June 22, 1926.

The present invention relates to a combination of one or more mercury switches of the type in which the mercury is contained in closed vessels in an atmosphere of a neutral gas with a compound thermo-electric element constituted by two metals having dissimilar coefficients of expansion, a change of temperature in which causes bending, this latter phenomenon being employed to produce tilting 10 of the switch, thus causing therein movements of the mercury necessary for its operation.

Electric switches with mercury contacts in a neutral gas have not hitherto received all the applications in electrical apparatus which 15 their great simplicity and great sureness of operation merit. This is due to the fact that this latter requires slow displacements of fairly large amplitude, which it is not always easy to realize with the ordinary electromag- 20 netic relays.

The same thing may be said of compound strips or thermo-electric elements by which is meant an aggregate of two metallic strips soldered together over the whole extent of one 25 surface of each of them, the metals constituting the two strips being selected with coefficients of expansion as different as possible.

Under these conditions any change of temperature in the bi-metallic strip is shown by 30 a change of curvature. This change of shape has already been used to close or to open electric contacts, but the weakness of the mechanical forces, which come into play generally necessitates somewhat considerable complica- 35 tions to ensure perfect operation.

The construction of mercury switches employed in carrying the invention into practice may be any whatever.

Fig. 1 shows an arrangement in which there 40 is a rigid attachment between a bi-metallic strip K and a mercury switch L. The bi-metallic strip K, which is located vertically when at rest and rigidly fixed at its upper end M, carries at its lower end a horizontal bar O 45 to which are attached the grips holding said switch L. The terminals of the latter as well as the free end of the bi-metallic strip are connected by flexible leads to fixed terminals N. While there has been shown as an example 50 the case of a reversing switch hung from a bi-

metallic strip heated by its own resistance, it is to be understood that with this arrangement there may be employed any type of mercury switch and that any of the usual means of heating the bi-metallic strip may be employed. 55

The sensitiveness of the device may be increased by compensating for the weight of the mercury switch by immersing it in a liquid having a density approximating its mean density as shown in Fig. 2; this arrangement has 60 the advantage of damping the oscillations caused by external vibrations.

Claims:

1. In combination, a mercury switch and a liquid bath surrounding said switch, said bath 65 having a density substantially equal to the average density of said switch.

2. In combination, a mercury switch, a thermo-sensitive element supporting said switch, and a liquid bath surrounding said 70 switch having a density substantially equal to the density of the switch.

In testimony whereof I affix my signature.

MAURICE AUGUSTE EUGÈNE LEBLANC.
